(57) **CLAIM**

The ornamental design for a poppymate pocket, as shown and described.

DESCRIPTION

FIG. 1 is a perspective view of the present invention in an open position;

FIG. 2 is a front view of the present invention;

FIG. 3 is a right side view of the present invention, the left side view being a mirror image thereof;

FIG. 4 is a back view of the present invention;

FIG. 5 is a top view of the present invention, the bottom view being a mirror image thereof;

FIG. 6 is another perspective view of the present invention in a closed position; and,

FIG. 7 is an alternate view of the present invention in a closed position attached to a user.

The broken lines in FIG. 7 immediately adjacent the solid lines represent the bounds of the claim, and the broken lines and the area within the broken lines represent unclaimed portions of the present invention. None of the broken lines form a part of the claimed design.
